Their Attorney.

UNITED STATES PATENT OFFICE.

ALBERT N. OTIS, OF SCHENECTADY, NEW YORK, AND LOUIS F. WOOLSTON, OF RICHMOND HEIGHTS, MISSOURI, ASSIGNEES TO GENERAL ELECTRIC COMPANY, A CORPORATION OF NEW YORK.

FURNACE.

Application filed March 12, 1927. Serial No. 174,364.

Our invention relates to furnaces and has for its object the provision of simple and reliable means whereby the heat stored in the charge when taken out of the furnace may be utilized to a large extent in preheating a cold charge.

Our invention has particular application to furnaces for heat treating metals, such as for annealing metals, such as brass and copper, although it obviously has application to furnaces in general. In carrying out our invention, we provide the usual furnace chamber provided with a source of heat, also a preheating chamber connected with the furnace chamber and provided with supporting means for the charge whereby the charge is first preheated in the preheating chamber by the heat given off from a cooling charge therein, a charge being heated at the same time in the furnace chamber. At the end of a heating operation the cooled charge in the preheating chamber is removed and the heated charge transferred from the furnace chamber to the preheating chamber, while the preheated charge is transferred to the furnace chamber and its place taken by a cold charge.

For a more complete understanding of our invention reference should be had to the accompanying drawing the single figure of which is a somewhat diagrammatic view in vertical section of an electric furnace embodying our invention.

Referring to the drawing, we have shown our invention in one form as applied to a furnace which is particularly adapted for annealing metals. In this furnace heat refractory walls 10 are provided to define two chambers, a furnace heating chamber 11 and a preheating chamber 12. These two chambers are placed adjacent each other and communicate through an opening 13 provided with a door 14 which may be raised vertically to open position. The furnace chamber 11 is provided with suitable heating means which, as shown, may be electric heaters 15 at the top of the chamber and electric heaters 16 in a suitable recess in the bottom of the chamber. A suitable rail or top plate 17 is provided on the bottom of the furnace chamber to support the charge. A door opening 18 closed by a vertical door 19 is provided at the opposite end of the furnace chamber although this door is not ordinarily used.

Access is had to the preheating chamber 12 through a door opening 20 closed by a vertically movable door 21. This chamber is not provided with heating means since its object is to facilitate the transfer of heat stored in a hot charge removed from the furnace chamber to a cold charge. To facilitate the movement of the charges in the preheating chamber a support is provided having two decks or platforms 22 and 23 arranged in vertically spaced relation. These decks or platforms are mounted on a suitable elevated device, such as a hydraulically operated piston elevator 24 so that the decks may be raised or lowered as the case may be to bring either one opposite the door openings 13 and 20.

In the operation of the furnace, three charges are utilized at the same time. These charges are shown in dotted lines and consist of a charge 25 in the furnace chamber which is being heated, a previously heated charge 26 in the preheating chamber which has just been removed from the furnace chamber and is now being cooled, and a cold charge 27 in the preheating chamber which is being preheated from the heat given off from the cooling charge 26. At the end of the heat treating operation for the charge 25, the door 21 is raised and the charge 26 removed from the preheating chamber. The door 14 is then raised and the charge 25 transferred from the furnace chamber to the platform 23 in the preheating chamber. The platforms 22 and 23 are now lowered by the device 24 until the platform 22 is on a level with the openings 13 and 20 after which the preheated charge 27 is moved into the furnace chamber 13 and a cold charge put in its place through the door opening 20. The doors 14 and 21 are now closed and the heating cycle repeated as previously described.

While we have described our invention as embodied in concrete form and as operating in a specific manner in accordance with the provisions of the patent statutes, it should be understood that we do not limit our invention thereto since various modifications thereof will suggest themselves to those skilled in the art without departing from the spirit of our invention the scope of which is set forth in the annexed claims.

What we claim as new and desire to secure by Letters Patent of the United States, is:

1. An annealing furnace comprising walls forming a heating chamber and a preheating chamber communicating therewith, heating means in said heating chamber, and a vertically movable member in said preheating chamber acting as a common support for a cold charge being preheated and a hot charge being cooled.
2. An annealing furnace comprising walls, forming a heating chamber and a preheating chamber communicating therewith, heating means for said heating chamber, and a movable support in said preheating chamber for a cold charge being preheated and a hot charge being cooled, said support being movable in said chamber to provide for the removal of a cooled charge from said preheating chamber, the transfer of a heated charge from said heating chamber to said preheating chamber, the transfer of a preheated charge from the preheating chamber into said heating chamber, and the insertion of a cold charge into said preheating chamber.
3. An annealing furnace comprising walls forming a heating chamber and a preheating chamber, said walls being provided with an opening leading into said preheating chamber and with an opening connecting said chambers, a movable support in said preheating chamber provided with spaces for preheating a cold charge and for cooling a heated charge, and means for moving said support to bring said spaces into registering relation with said openings to effect the removal of

the cooled charge, the transfer of a hot charge from the heating chamber to the preheating chamber, the transfer of a preheated charge from the preheating chamber to the heating chamber, and the insertion of a cold charge into said preheating chamber.

4. An annealing furnace comprising walls forming a heating chamber and a preheating chamber communicating therewith, heating means in said heating chamber, and an elevating device in said preheating chamber having decks providing supports for a cool charge being preheated and a hot charge being cooled while a third charge is being heated in said heating chamber.

5. An annealing furnace comprising walls forming a heating chamber and a preheating chamber communicating therewith through a door opening, heating means in said heating chamber, a vertically movable support in said preheating chamber having double decks providing supports for a cold charge being preheated and a hot charge being cooled while a third charge is being heated in said heating chamber, and means for adjusting said support in a vertical direction to bring said decks into alignment with said door opening.

In witness whereof, we have hereunto set our hands respectively the 3d day of March 1927, and the 9th day of March 1927.

ALBERT N. OTIS.
LOUIS F. WOOLSTON.
